HENRY LUSSIER, OF SALEM, MASSACHUSETTS, ASSIGNOR TO DRAPER CORPORATION,
OF HOPEDALE, MASSACHUSETTS, A CORPORATION OF MAINE.

STOPPING MECHANISM FOR LOOMS.

1,342,555.

Specification of Letters Patent. Patented June 8, 1920.

Application filed January 24, 1919. Serial No. 272,832.

To all whom it may concern:

Be it known that I, HENRY LUSSIER, a citizen of the United States, residing at Salem, county of Essex, State of Massachusetts, have invented an Improvement in Stopping Mechanism for Looms, of which the following description, in connection with the accompanying drawing, is a specification, like characters on the drawing representing like

parts. This invention has for its object to provide a simple and effective mechanism for stopping the loom under all conditions through the action of protector mechanism such as that the action of which is initiated through the failure of the shuttle to become properly boxed at either end of the pick.

The invention is especially applicable to wide looms wherein it is necessary to provide mechanism at both sides of the loom to insure the operation of the stopping mechanism. The general principle of such mechanism is illustrated in the patent to Stimpson No. 726,589 granted April 28, 1903, wherein a frog is provided at each side of the loom and in which either frog when moved operates through certain connections to throw off the power. In the present invention the power controller and brake mechanism is preferably of the type disclosed in the patent to Ambler No. 867,934 granted October 8, 1907. In this construction the lever or handle by which the power controller is actuated, and also the lever or handle by which the brake mechanism is operated swings forwardly to running position and rearwardly to throw off the power and set the brake mechanism. In this construction also the power controller is brought to running position through the agency of a starter rod rotatably journaled at the front of the breast beam, extending across the loom, and provided with a plurality of handles so that the starter rod may be operated at a number of different points to bring the power controller to running position.

One feature of the present invention resides in transmitting the movement of the frog at the side of the loom opposite the power controller to the power controller through the starter rod so as to operate the power controller to throw off the power without interfering with the use of the

starter rod as a means for bringing the power controller to running position. 55

Another feature of the invention resides in an improved and effective means for transmitting the movement of the frog at the side of the loom opposite the power controller to the power controller to operate the 60 same to throw off the power.

The invention is of value irrespective of the particular source of power employed for operating the loom but is particularly useful when the loom is run by an individual 65 electric motor clutched to the shaft of the loom. If upon the actuation of the protector mechanism the power is not thrown off the lay may be locked while the motor will continue to run thus slipping the clutch and 70 in all probability causing the motor to burn out. Such a result is prevented in a simple and effective manner by this invention.

These and other objects and features of the invention will appear more fully from 75 the accompanying description and drawings and will be particularly pointed out in the claims.

In the drawings

Figure 1 is a view in side elevation of so 80 much of a loom of the well known Northrop type provided with an individual electric motor and with a preferred form of the present invention as is necessary to a disclosure of the invention; 85

Fig. 2 is a view in end elevation and partially in vertical cross section of a portion of the said loom looking toward the side of the loom at which the filling carrier hopper is located or at that side opposite the side at 90 which the power controller is located;

Fig. 3 is a detail of the construction shown in Fig. 2 with the parts illustrated in position for knocking off or operating the power controller; 95

Fig. 4 is a detail in front elevation of the construction shown in Fig. 3.

Inasmuch as the protector mechanism and the power controlling mechanism and brake mechanism and the general construction of 100 the loom herein illustrated is of a familiar and well known type and in its main features is fully illustrated and described in the before-mentioned patent to Ambler it is unnecessary here to describe the same in detail. 105

In the construction illustrated the main

- driving shaft 5 of the loom carries a gear 6 driven from a pinion 7 on the shaft 8 of an individual electric motor 9. A clutch between the gear 6 and its shaft 5 is controlled 5 through connections such as described in the before-mentioned patent to Ambler from a power controller shown as a lever 10, fulcrumed at 11 on the left hand side frame 12 of the loom. When this power controller 10 is in its forward position resting against the stop 13 as shown in Fig. 1 the clutch is in engagement and the connections are in running position. When the power controller 10 is swung rearwardly the clutch is disconnected to throw off the power and the power controller comes against the stop 14. Suitable brake mechanism is provided such for example as shown in the before-mentioned patent to Ambler including an 20 annular member 15 mounted upon the crank shaft 16 of the loom and encircled by a friction brake band 17 having connection with a brake lever 18 also fulcrumed at 11. When the brake lever 18 is in forward position, 25 as shown in Fig. 1, the brake band is released. The brake lever 18 when swung to rearward position acts to swing rearwardly the power controller 10 through the agency of the screw 19 contacting with the depending arm 20 and when thus swung to rearward position acts through the connections to bring the brake band into frictional engagement with the annular member 15 and thus set the brake mechanism. 30 35 A starter rod 21 is rotatably journaled in bearings at the front of the breast beam and extends across the loom. At suitable intervals of its length it is provided with handles 22 having a lost motion connection therewith. At the power controller side of the loom an arm 23 projects from the starter rod and is adapted at its lower end to engage behind a stud 24 projecting laterally from the power controller 10. Hence the 40 operator standing at any position in front of the loom by seizing and elevating one of the handles 22 is enabled to swing the power controller forwardly and bring it to running position. 45 50 The protector mechanism illustrated is of that type which is actuated by the failure of the running shuttle to become properly boxed at either end of the pick. Such a protector mechanism includes a frog 25 mounted to slide forwardly and rearwardly on the loom frame at the power controller side and another frog 26 mounted to slide in a similar manner on the opposite side frame 27 of the loom. These frogs are 55 60 65 caught and moved forwardly by daggers, one of which 28 is shown projecting from a protector shaft 29 mounted on the lay. Upon the beat up of the lay if the shuttle fails properly to enter either box at the end of its pick one or the other of the binder

fingers 30 enters the shuttle box allowing the daggers to drop into engagement with the frogs and thus as the beat up of the lay concludes to move the frogs forwardly. It is desirable that such a movement of each 70 of the frogs shall effect the operation of the power controller so that if for any reason one of the frogs is not properly actuated the one which is actuated, whichever one it may be, will effect the throwing off of the power. 75

The frog 25 at the power controller side of the loom is provided with a depending bunter 31 so that when it is moved forwardly it contacts directly with the depending portion 20 of the brake lever 18 and acts therethrough to swing the brake lever and simultaneously the power controller 10 rearwardly to throw off the power and set the brake mechanism. 80

The present invention is concerned more 85 particularly, however, with securing the operation of the power controller, and also the brake mechanism from the frog 26 at the opposite side of the loom. For this purpose the starter rod 21 is preferably utilized and 90 in such a way as not to interfere with its operation as a starter rod. In the construction illustrated a lever of the bell crank type 32 is fulcrumed at 33 on the loom side adjacent the frog 26 with one arm 95 extending toward the frog while the other arm extends upwardly adjacent the starter rod. Another arm 34 is secured to the starter rod and projects above the end of the bell crank lever 32 and into the path 100 of the same. At the opposite side of the loom an operative connection is made between the starter rod and the power controller and as a simple means for securing this connection the arm 23 already described 105 may be provided with a lug 35 projecting laterally therefrom so as to come opposite the front edge of the power controller or lever 10. 110

If now the frog 26 be moved forwardly it will contact with the lever 32 and swing this lever about its pivot, the lever in turn striking the arm 34 will rotate or rock the starter rod 21, in the direction opposite to that which takes place when the starter 115 rod is employed to start the loom, and consequently will swing the arm 23 rearwardly and bring the lug 35 into engagement with the power controller 10 thus operating the power controller to throw off the power and consequently through the mechanism already described simultaneously operate the brake lever 18 to set the brake mechanism. 120 Thus it will be seen that the movement of the frog 26 at the side of the loom opposite the power controller is effectively and accurately transmitted to the power controller to effect the operation of the power controller to throw off the power and also, when the brake mechanism is employed, to set 125 130

the brake mechanism. It will also be seen that this is effected preferably through the usual starter rod without in any way interfering with the normal function of the 5 starter rod.

Having fully described my invention, what I claim as new and desire to secure by Letters Patent is:

1. A loom comprising protector mechanism including a frog at one side of the loom, a power controller at the opposite side of the loom, a starter rod extending across the loom and operative when rotated in one direction to move the power controller to running position, and means governed by or through movement of said frog acting to rotate said starter rod in the opposite direction and therethrough to operate the power controller to throw off the 20 power.
2. A loom comprising protector mechanism including a frog at one side of the loom, a power controller at the opposite side of the loom, brake mechanism for the 25 loom, a starter rod extending across the loom and operative when rotated in one direction to move the power controller to running position, and means governed by or through movement of said frog acting to 30 rotate said starter rod in the opposite direction and therethrough to operate the power controller to throw off the power and to effect the setting of the brake mechanism.
3. A loom comprising protector mechanism including a frog at one side of the loom, a power controller at the opposite side of the loom, a rod rotatably mounted upon and extending across the loom, a lever 35 engaged and rocked by said frog upon the movement thereof, an arm projecting from said rod into the path of said lever, and means for causing the said rod when rotated by said arm to operate the power controller to throw off the power.
4. A loom comprising protector mechanism including a frog at one side of the loom, a power controller at the opposite 45

side of the loom, brake mechanism for the loom, a rod rotatably mounted upon and 50 extending across the loom, a lever engaged and rocked by said frog upon the movement thereof, an arm projecting from said rod into the path of said lever, and means for causing the said rod when rotated by 55 said arm to operate the power controller to throw off the power and to effect the setting of the brake mechanism.

5. A loom comprising protector mechanism including a frog at one side of the 60 loom, a power controller at the opposite side of the loom, a starter rod rotatably journaled upon and extending across the loom, an arm projecting from said starter rod adjacent the power controller and acting when swung in one direction to move the power controller to running position and when swung in the opposite direction to operate the power controller to throw off the power, and means governed by or 70 through the movement of said frog acting to rotate said starter rod to swing said arm in the direction required to operate the power controller to throw off the power.

6. A loom comprising protector mechanism including a frog at one side of the loom, a power controller at the opposite side of the loom, a starter rod rotatably journaled upon and extending across the loom, an arm projecting from said starter 80 rod adjacent the power controller and acting when swung in one direction to move the power controller to running position and when swung in the opposite direction to operate the power controller to throw off the power, a lever engaged and rocked by said frog upon the movement thereof, a second arm projecting from the starter rod into the path of said lever and operated by said lever upon the movement of said 90 frog to rotate the starter rod in the direction required to operate the power controller to throw off the power.

In testimony whereof, I have signed my name to this specification.

HENRY LUSSIER.
